E. Ripley, Troy, N. Y. Letters Patent No 194
dated August 10 1848 - (assigned to Johnson & Cox)

Des. 194

The Schedule referred to in these Letters Patent
and making part of the same

To all to whom these presents shall come: Be
it known that I, Ezra Ripley of Troy in the County
of Rensselaer and State of New York have invented or
produced a new design for stove plates; and that the
following is a full, clear and exact description of the
same, reference being had to the accompanying draw-
ings, making part of this specification in which Fig. 1 is
a view of the front plate of an "American Cottage
Air Tight" Parlor Stove. This plate is shown in the
drawings is ornamented in the centre with a carved
tablet about ten inches in width marked Fig. 3 and
directly above the same is a carved moulding and an
either end of said plate is a Gothic niche marked Fig.
4. I claim as my invention and desire to secure by
Letters Patent the above design which is fully set forth
in the drawings accompanying this description
